UNITED STATES PATENT OFFICE.

GUY M. SPEAR, OF WALTHAM, AND AUSTIN T. SYLVESTER, OF NEWTONVILLE, MASSACHUSETTS.

DESIGN FOR A SPOON, &c.

SPECIFICATION forming part of Design No. 20,789, dated June 2, 1891.

Application filed February 13, 1891. Serial No. 381,361. Term of patent 3½ years.

To all whom it may concern:

Be it known that we, GUY M. SPEAR and AUSTIN T. SYLVESTER, citizens of the United States, and residing, respectively, at Waltham and Newtonville, both in the county of Middlesex and State of Massachusetts, have invented and produced a new and original Design for Handles for Spoons, Forks, and the Like, of which the following is a specification.

Our design is adapted for use on the handles of table silver-ware, such as spoons, forks, and other like articles.

The accompanying drawings forming a part of this specification, shows a spoon having a handle embodying our design.

The leading feature of our design consists

in the handle of a spoon, fork, or other like article having thereon the representation of the front or dial of a watch, as shown in the drawing.

We claim—

The design for the handles of spoons, forks, and the like, substantially as shown and set forth.

In testimony whereof we have signed our names to this specification, in the presence of two subscribing witnesses, this 9th day of February, A. D. 1891.

GUY M. SPEAR.

AUSTIN T. SYLVESTER.

Witnesses:

C. F. BROWN,

A. D. HARRISON.
